UNITED STATES PATENT OFFICE.

JHUE RUSSELL EARP, OF CHATTANOOGA, TENNESSEE, ASSIGNOR OF ONE-HALF TO
BENJAMIN SILVERMAN, OF CHATTANOOGA, TENNESSEE.

COMB.

Application filed November 7, 1923. Serial No. 672,255.

To all whom it may concern:

Be it known that I, JHUE RUSSELL EARP, citizen of the United States, residing at Chattanooga, in the county of Hamilton 5 and State of Tennessee, have invented certain new and useful Improvements in Combs, of which the following is a specification.

This invention relates to hair dressing 10 and has special reference to a device for straightening wavy or kinky hair.

More particularly the invention relates to an improved hair straightening comb.

One important object of the invention is 15 to provide a novel comb of this character having an improved general construction.

A second important object of the invention is to provide a novel comb for this purpose having a toothed portion provided 20 with a back and teeth held together in an improved manner.

A third important object of the invention is to provide a novel arrangement of such a comb wherein the handle and tooth 25 portions may be separated without disarranging or displacing the teeth.

A fourth important object of the invention is to provide a handle and a novel reversible toothed portion having curved metallic teeth, the reversing of the tooth portion on the handle serving to change the direction of curvature of the teeth relative 30 to the handle.

A fifth important object of the invention 35 is to provide novel and efficient means for holding the handle on the toothed portion.

With the above and other objects in view as will be hereinafter apparent, the invention 40 consists in general of certain novel details of construction and combinations of parts hereinafter fully described, illustrated in the accompanying drawings and specifically claimed.

In the accompanying drawings like characters of reference indicate like parts in the several views, and:

Figure 1 is a side elevation of a comb 45 constructed in accordance with this invention and having curved teeth.

Figure 2 is a view thereof partly in section and with the teeth removed.

Figure 3 is a view similar to Figure 1 but having straight teeth.

Figure 4 is a vertical longitudinal section through the comb shown in Figure 3. 55

Figure 5 is an end view of Figure 1.

Figure 6 is an end view of Figure 1 with teeth reversed from the position shown in 60 Figure 5.

Figure 7 is a section on the line 7—7 of Figure 3.

Figure 8 is a perspective detail of one of the straight teeth.

In the present embodiment of the invention there is provided a handle 10 having an opening 11 therethrough. On one end of this handle is a ferrule 12 and through the handle and ferrule extends a rod 13. 65

On the projecting portion of the rod 13 70 is carried the comb proper which includes a back 14 of substantially elliptical form in cross section and provided with an opening 15 through which said rod passes. At one end of the opening there is provided an offset end 17 of the rod 13 thus preventing 75 the rotation of the back on the rod when the handle and back are assembled and the thumb nut 18, used to hold these parts in assembled relation, is screwed up. 80

Spaced slots 19 are formed in the back to receive the butt portions of the teeth 20 which may either be of the straight form shown in Figure 7 or the curved form shown in Figure 6. Through the portions 85 of the back between the slots 20 extends a series of aligned openings 21 for the reception of a tooth retaining rod 22 which passes through elongated openings 23 formed in the teeth adjacent these base portions, said base portions being provided with concave ends to fit against the bar 13. The rod 22 is held at one end by an overlapping portion of the end 17 and at its other end by engagement of the ferrule 12. 90

It will now be apparent that the toothed portion of the device can be removed from the handle as a unit and replaced after being turned end for end. Thus a comb having teeth curved to the right may be readily changed so that the teeth curve to the left. 95

There has thus been provided a simple and efficient device of the kind described and for the purpose specified. 100

Having thus described the invention, what is claimed as new, is:

1. A back having spaced slots extending 105

transversely thereof, teeth having their butt portions located in said slots, a tooth-retaining rod passing through the portions of the back between said teeth and through the butt portions of the teeth, a handle, and a rod slidably passing through the back and handle and having a head engaging the end of the back remote from the handle and covering the corresponding end of the first rod, and means for securing the rod in the handle.

2. A back having spaced slots extending transversely thereof, teeth having their butt portions located in said slots, a tooth-retain-

ing rod passing through the portions of the back between said teeth and through the butt portions of the teeth, a handle, and a rod slidably passing through the back and handle and having a head engaging the end of the back remote from the handle and covering the corresponding end of the first rod, means for securing the rod in the handle, said rod head being formed by an offset portion of the rod and the back being provided at each end with a recess to receive said offset portion.

In testimony whereof I affix my signature.
JHUE RUSSELL EARP.
